UNITED STATES PATENT OFFICE.

WILLIAM J. TANGERMAN, OF HAMMOND, INDIANA.

UNCOUPLING DEVICE.

1,404,806.

Specification of Letters Patent. Patented Jan. 31, 1922.

Application filed March 12, 1921. Serial No. 451,671.

To all whom it may concern:

Be it known that I, WILLIAM J. TANGERMAN, a citizen of the United States, and a resident of Hammond, Lake County, Indiana, have invented certain new and useful Improvements in Uncoupling Devices, of which the following is a specification.

My invention relates generally to means for uncoupling railroad cars, but has particular reference to means for pulling or withdrawing the pin which is used to lock the knuckle of a car coupler.

It formerly was the practice to provide a rod extending transversely of the end of the car which, in turn, was connected to the pin through the medium of a clevis and chain. In use the chain gave much trouble, due to buckling thereof and as a result lost the approval of the Master Car Builders' Association, which now requires that the connection be direct between the lifter and the pin, i. e. without any such flexible member as a chain, cable or the like. Several forms of pin lifters have been devised to meet the M. C. B. requirements, but these are open to objection on several grounds. In some of them, the range of movement is limited and there is danger when the car coupler moves longitudinally, as it does in use, to pull upwardly on the locking pin and release the knuckle, thus inadvertently uncoupling the cars. Some of the proposed pin lifters are also open to the objection that in the event the end portion thereof becomes broken, part of the device will fly backwardly toward the brakeman and instances have occurred where the flying portion has caused severe injury to the brakeman. To remedy this objection the M. C. B. rules state that a stop lug or casting must be affixed to such construction to prevent such action in the event of breakage.

Some of the constructions heretofore proposed are also open to the objection that the broken part thereof may, under certain conditions, fly backwardly even though a lug is provided for the purpose of intercepting the flying missile. There is danger when it does miss the stop of hitting the brakeman or other attendant. In such constructions the stop is also difficult of attachment and when attached cannot be said to operate satisfactorily.

The general object of my invention is to provide a pin lifter construction which shall be simple, inexpensive and durable, and

which shall be safe and effective under all conditions.

Again it is an object of my invention to provide a pin lifter construction which shall be free for easy automatic adjustment to different positions to the end that any tendency to pull or lift the pin when the coupler moves shall be eliminated.

A further object of my invention is to provide a pin lifter construction such that those heretofore employed can be readily converted, at little expense, into constructions embodying my invention.

I aim also to provide a construction of such form that even when broken no part can fly away and thus obviate the necessity of stop lugs or other missile intercepting devices.

My invention consists generally in the form, arrangement, construction and co-operation of the parts whereby the above named objects, together with others that will appear hereinafter, are attainable; and my invention will be more readily understood by reference to the accompanying drawings which illustrate what I consider, at the present time, to be the preferred embodiment thereof.

In said drawings: Fig. 1 is a fragmentary plan view of the end of a car equipped with a device embodying my invention.

Fig. 2 is a fragmentary end elevation of the parts shown in Fig. 1, and Fig. 3 is a fragmentary side elevation.

No attempt has been made to illustrate the car or coupler in detail as they form no part of the invention. 1 represents the body of the car in or upon which the usual coupler 2 is mounted. It will be understood that the coupler 2 is attached through the medium of a draft gear (not shown). Thus at times it will occupy the full line position in Fig. 1 and at other times may occupy different positions of which the dotted positions 2^a and 2^b are representative. The coupler is provided with a knuckle member 3 which is mounted upon a vertical pivot 4 to permit swinging movement in a horizontal plane in well known manner. A knuckle pin or lock 5 is provided, the function of which is to prevent swinging movement of the knuckle. The parts thus far described are or may be of usual or desired construction.

The pin 5 is provided with an eye 6 hav-

ing a circular opening therein through which I pass the cylindrical end portion 7 of the member 8, hereinafter termed a pin lever arm. The pin lever arm is preferably 5 a forging and at one end is flattened to provide the relatively broad slab-like portion 9, which in turn is provided with two spaced holes 10 and 11. Through the holes 10 and 11 I pass the hook-like end of what I term 10 the uncoupling rod. The uncoupling rod, as here shown, is composed of a straight part 12 which is supported for rotation in brackets 13 and 14 carried by the car. One end 15 is bent at right angles to the portion 15 12 and forms a handle portion for swinging the uncoupling rod. The other end portion as stated is in the form of a hook formed of the spaced portions 16 and 17 connected by the curved portion 18 which follows 20 the arc of a circle. The holes 10 and 11 are slightly larger than the accommodated portions of the hook so that the pin lever arm may readily adjust itself thereon.

Operation.—To lift the pin 5 the handle 25 15 of the uncoupling rod is swung from the full line position shown in Fig. 3 to the dotted position. As the coupler moves back and forth in operation the pin lever arm readily adjusts itself on the hook supporting portion of the uncoupler rod, following 30 the curved portion thereof. The cylindrical portion of the pin lever arm easily slides back and forth through the eye of the coupler pin. A stop 19 prevents the uncoupling 35 rod handle from swinging downwardly more than is desired.

The present construction has a number of advantages, among which may be noted the absolute freedom of movement, such as will 40 eliminate any tendency to pull the pin when the coupler moves longitudinally either forwardly or backwardly. The safety construction preventing parts from flying in event the device becomes broken thus obviates the necessity of providing a stop lug 45 to prevent flying of broken parts. This, of course, simplifies and cheapens the construction. There are only two parts to the device which are secured together without the use of any bolts or nuts and there is absolutely nothing that can loosen or get out of order. The construction is such that much 50 of the old equipment used in pin lifting can be utilized in the present construction. All

that is necessary to convert an old type pin lifter to the present one is to cut off a piece of the lifter rod and then bend the end portion (indicated by dotted lines at 20—Fig. 1) backwardly in the form of the hook previously described. 60

In the claims where the term coupler pin is used it shall be construed broadly to mean either a pin or other lock for engagement with knuckle.

The many advantages of my invention 65 will be obvious to those skilled in this art without further comment, but since this disclosure will readily suggest to others modified constructions whereby the substantial objects and purposes of my invention may be attained, I do not wish to be limited to the specific construction herein shown and described, except only as may be necessary by limitations in the hereunto appended claims. 75

I claim:—

1. An uncoupling device embodying therein a pin lever arm and an operating rod therefor, one of said members having a curved end portion and the other having openings 80 in spaced portions thereof through which said curved portion of the other member extends.

2. An uncoupling device embodying therein a pin lever arm and an operating rod 85 therefor, said pin lever arm having two spaced openings therein, and said operating rod having a curved end portion extending through said spaced openings.

3. An uncoupling device embodying there- 90 in a pin lever arm and an operating rod therefor, said pin lever arm having two spaced openings therein, and said operating rod having a curved end portion extending through said spaced openings, said curved 95 portion of the operating rod being smaller than said openings in order to permit free relative movement of the parts.

4. An uncoupling device embodying there- 100 in a pin lever arm and an operating rod therefor, said pin lever arm having a flattened end portion provided with two spaced openings, and said operating arm having a curved end portion extending through said openings. 105

In testimony whereof, I have hereunto set my hand, this 26th day of January, 1921.

WILLIAM J. TANGERMAN.
